UNITED STATES PATENT OFFICE.

PAUL H. SCHENDLER, OF ERIE, PENNSYLVANIA, ASSIGNOR TO LOVELL MANUFACTURING COMPANY, OF ERIE, PENNSYLVANIA, A CORPORATION OF PENNSYLVANIA.

COMPRESSING-ROLLS AND MOUNTINGS THEREFOR.

1,137,028.

Specification of Letters Patent. Patented Apr. 27, 1915.

Application filed January 31, 1910. Serial No. 540,974.

To all whom it may concern:

Be it known that I, PAUL H. SCHENDLER, a citizen of the United States, residing at Erie, in the county of Erie and State of Pennsylvania, have invented new and useful Improvements in Compressing-Rolls and Mountings Therefor, of which the following is a specification.

This invention relates to compressing rolls and mountings therefor, and consists in certain improvements in the construction thereof, as will be hereinafter fully described and pointed out in the claims.

The invention is illustrated in the accompanying drawings wherein it is shown as a clothes wringer as follows:

Figure 1 is an end view of the wringer; Fig. 2 an elevation partly in section on the line 2—2 in Fig. 1 of one end of the wringer; Fig. 3 is a side elevation of a bearing lever and gear housing; Fig. 4 a section on the line 4—4 in Fig. 3; Fig. 5 a perspective view of the bearing lever; Fig. 6 a perspective view of the securing plate; and Fig. 7 a perspective view of the housing.

1 marks the upper roll; 2 the lower roll; 3 the shaft for the upper roll; 4 the shaft for the lower roll; 7 the bearing for the upper shaft; 8 the bearing for the lower shaft.

30 The bearing 7 is carried by the mounting 9 on the bearing lever 10. The bearing 8 is carried by the mounting 11 on the bearing lever 12. The levers 10 and 12 extend transversely to the axes of the rolls. The bearing lever 10 terminates in the post 13 which extends through and against the lever 12 acting as a fulcrum for the levers. A pressure post or bolt 14 extends through the levers from the clamp 15, the clothes guide 16 being secured between the clamp 15 and the lever 12. The post 14 is screwthreaded at its upper end and provided with a thumb nut 17. A spring 18 is arranged around the bolt and between the lever 10 and the nut 17. 45 The levers at the opposite sides of the wringer are connected by the clothes guide 16 and the top bar 19. The parts so far described are similar to those used in a well known type of wringer.

50 Many attempts have been made to provide a wringer of this type with gears arranged within the frame but difficulty has been experienced in providing a suitable housing for the gears.

In the present construction, the gear 5 is arranged on the upper shaft 3, and the gear 6 on the lower shaft 4, and the housing 20 is provided for these gears. The housing is shown in detail in Figs. 3 to 7. The main part of the housing comprises a peripheral wall 20^a which extends around the gears and the plate 20^b having the slot 21. This plate 20^b is arranged between the gears and the rolls. The shafts 3 and 4 extend through the slot 21. The wall 20^a is provided with the notches 22 and the lugs 23. A securing plate 24 has the slot 25 through which the shafts 3 and 4 extend and the lugs 26 correspond to the notches 22. In securing the plate to the wall of the housing, the plate is placed within the wall 20^a of the housing, as is clearly shown in Fig. 3, with the lugs 26 in the notches 22. The lugs 23 are then upset, and bent down over the plate. Wringers of this type of course require galvanizing, and where the plate telescopes the wall of the housing, the subsequent galvanizing completes the union between the plate and the wall of the housing.

The plate is provided with the perforations 27 through which lugs 28 on the mounting 9 extend. The mounting is provided with a face 29 against which the plate rests. The lugs are headed down after the plate is in place on the mounting so as to be thus firmly secured to the mounting. In ordinary practice, the plate is first secured to the mounting then the housing to the plate. In this manner the housing is firmly secured to the bearing lever, and carried with it. It is thus maintained in position with relation to the gears, and the bearings so as to utilize but little space and yet allow the free running of the rolls and gears. It is also free from any rattling which is incident to a housing loosely mounted.

The mountings at both ends of the wringer are duplicates, except that the faces are reversed at the end opposite the one shown.

100 What I claim as new is:

1. In compressing rolls and mountings therefor, the combination of two rolls; two bearing levers extending transversely from the rolls and having a swinging connection at their outer ends to permit a to and from movement at their inner ends; bearings one for each roll carried by said levers and a

guard plate secured to one of the levers and extending between the rolls and the bearings.

2. In compressing rolls and mountings therefor, the combination of two rolls; bearing levers extending transversely from the rolls; bearings for the rolls carried by the levers; gears between the levers and the rolls; and a housing for the gears carried by one of the levers.

3. In compressing rolls and mountings therefor, the combination of two rolls; two bearing levers extending transversely from the rolls and having a swinging connection at their outer ends to permit a to and from movement at their inner ends; bearings, one for each roll carried by the levers; gears, one for each roll between the bearings and the rolls; and a housing for the gears carried by one of the levers comprising a peripheral wall, and a plate between the gears and the rolls.

4. In compressing rolls and mountings therefor, the combination of two rolls; bearings for the rolls; bearing mountings for the bearings; gears between the mountings and the rolls; a housing for the gears comprising a peripheral wall and a plate between the gears and the rolls; and a plate on the mounting side of the housing carried by the mounting.

5. In compressing rolls and mountings therefor, the combination of two rolls; bear-

ings for the rolls; bearing mountings for the bearings; gears between the mountings and the rolls; a housing for the gears comprising a peripheral wall and a plate between the gears and the rolls; and a plate telescopically arranged in the walls of the housing and secured therein by upsetting the walls of the housing and galvanizing the housing, said plate being carried by the mounting.

6. In compressing rolls and mountings therefor, the combination of two rolls; two bearing levers extending transversely from the rolls and having a swinging connection at their outer ends to permit a to and from movement at their inner ends; bearing mountings on the levers; bearings, one for each roll, carried by the mountings; gears, one for each roll, between the bearings and the rolls; a housing for the gears comprising a peripheral wall; a plate between the gears and the rolls; and a securing plate between the bearings and the gears secured to the mounting and the housing, and forming a means of connection between the mounting and the housing.

In witness whereof, I have hereunto set my hand in the presence of two subscribing witnesses.

PAUL H. SCHENDLER.
